UNITED STATES PATENT OFFICE.

FRANK J. FREY, OF QUINCY, ILLINOIS, ASSIGNOR TO C. H. WURST COMPANY, OF QUINCY, ILLINOIS.

DESIGN FOR A COOKING-RANGE.

No. 38,028.

Specification for Design.

Patented May 22, 1906.

Application filed April 5, 1906. Serial No. 310,180. Term of patent 7 years.

To all whom it may concern:

Be it known that I, FRANK J. FREY, a citizen of the United States, residing at Quincy, in the county of Adams and State of Illinois, have invented a new, original, and ornamental Design for Cooking-Ranges, of which the following is a specification, reference being had to the accompanying drawing, forming part thereof.

The figure is a perspective view of a cooking-range embodying my new design.

I claim—

The ornamental design for a cooking-range as shown.

FRANK J. FREY.
